UNITED STATES PATENT OFFICE

162,338

PUPPET OR SIMILAR ARTICLE

Mildred May Osgood, New York, N. Y.

Application October 25, 1950, Serial No. 12,709

Term of patent 14 years

(Cl. D34—15)

To all whom it may concern:

Be it known that I, Mildred M. Osgood, a citizen of the United States of America, and resident of the city, county, and State of New York, have invented a new, original, and ornamental Design for a Puppet or Similar Article, of which the following is a specification, reference being had to the accompanying drawing, forming a part thereof, in which

Fig. 1 is a front view of a puppet or similar article, embodying my design; and

Fig. 2 is a side view thereof.

I claim:

The ornamental design for a puppet or similar article, as shown.

MILDRED MAY OSGOOD.
